No. 352,949. Patented Nov. 23, 1886.

DISCAL INDICATOR.

W. GRIFFITH.

(No Model.)

WM. GRIFFITH.

W **addresses:**
A. S. BRYDEN,
JOSEPH HILLEMAN.

69 In the modification shown in Fig. 3 the de-
vice is somewhat smaller than either of those
described, and is used more particularly as a
beadheader, the mounts from January to June
being consequently displayed through the slot
on one side, while the other from July to
December are displayed on the other side.
The spaces in this modification are subdivided
longitudinally into seven narrower spaces, as is
evident from the calendar, each subdivided
diatting toward its corresponding initial letter
of the day of the week, which is located on
the narrow strip between the slot b and the
periphery of the disk. Each space may be
several parts subdivided without disturbing
from the spirit and scope of my invention;
whereas I do not wish to limit myself strictly to
the narrow construction set forth; but,
Having fully described my invention, what I
claim as new, and desire to secure by Letters
Patent, is—

70 2. The combination, with a plate having
each plate pivoted thereto and similarly provided
with characters, those on the inner faces of
each disk being displayed through the slot of
the adjacent plate, substantially as set forth. 100
71. An indicator composed of a series of two
disks pivoted together at the center, each disk
provided with slots, through which characters
on the inner faces of the disks are read, sub-
stantially as set forth.

72. The plate having a plate having
each plate pivoted thereto and similarly provided
with characters, those on the inner faces of
each disk being displayed through the slot of
the adjacent plate, substantially as set forth. 95

elite and Wyoming Valley trains north and 55 south. By an opposite arrangement of the spaces in a d, e, etc., on the two disks, while one side opens over the morning schedule of trains on a certain road, the opposite side opens over the corresponding schedule of evening trains for the same road. 60

10 My invention relates to an improvement in the same.
11 Invention, and exact description of the invention-
12 art to which my object relates is to provide a device
13 which may be carried conveniently in the pocket and attached, if desired, to some device
14 which may be carried in the pocket and convenient-
15 ble connection, or in a form convenient for
16 hanging on the wall.
17 With these ends in view my invention con-
18 sists in certain features of construction and
19 combination of parts, as will be hereinafter
20 fully described, and pointed out in the claims.
21 In the accompanying drawings, Figure 1 is
22 a front view of one disk improved device with a
23 portion of my improved drawings, Figure 2 is
24 a perspective and forms an alternative
25 disk may be employed, but the eye is
26 intended to pivot at the center by an
27 eye, a. Any convenient means for joining
28 the disks may be used together at the
29 center of a pair of disks, prefer-
30 ably of paper or pasteboard, and conven-
31 iently pivoted together at the center by an
32 eye, a. Any convenient means for joining
33 the disks may be employed, but the eye is
34 attached a cord, ribbon, or other flexible connec-
35 tion to prevent the device from displace-
36 ment. Each disk is provided with a slot, b, which
37 may be round, square, or any other conve-
38 nient shape, though for obvious reasons a U-
39 shaped slot is preferable, since by that con-
40 nection the entire surface of the interior
41 structure of the device is exposed to the slot
42 into spaces corresponding in size to the slot
43 dividing the adjacent faces of the indicator
44 each set of figures or characters may be
45 kept confined within a space. Each space may
46 be used as a time-table for a separate rail-
47 road. For example, in Fig. 1 space d gives
48 the time of all the trains on the Delaware, Lack-
49 awanna, and Western division. In a similar manner
50 space e gives the time of all the trains on the South from Pittsburg.

Application filed June 15, 1886.

WILLIAM GRIFFETTI, OF PITTSTON, PENNSYLVANIA.

DISCAL INDICATOR.

UNITED STATES PATENT OFFICE.
